DISPLAY BOX

Michael King, Pleasure Ridge Park, Ky., assignor to Mother's Cookie Company, Louisville, Ky., a corporation of Kentucky

Filed Jan. 3, 1967, Ser. No. 5,295

Term of patent 14 years

(Cl. D9—224)

FIG. 1

FIG. 1 is a top perspective view of a display box showing my new design;

FIG. 2 is a top plan view thereof;

FIG. 3 is a side elevational view thereof; and

FIG. 4 is an end elevational view thereof.

The side and end of the box which are not visible in FIG. 1 have the same appearance as the respective side and end which are visible, and the bottom of the box is plain and unornamented.

I claim:

The ornamental design for a display box, as shown and described.
